CLAIM

The ornamental design for a monitor, as shown and described.

DESCRIPTION

FIG. 1 is a perspective view of the monitor showing my new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left side elevational view thereof, the side opposite being a mirror image of that shown.

1 Claim, 2 Drawing Sheets
